UNITED STATES PATENT OFFICE.

OTTO F. KLOETZER, OF WASHINGTON, INDIANA.

ORDER-HOOP HOLDER.

Application filed March 28, 1921. Serial No. 456,343.

To all whom it may concern:

Be it known that I, OTTO F. KLOETZER, a citizen of the United States, residing at Washington, in the county of Daviess and 5 State of Indiana, have invented new and useful Improvements in Order-Hoop Holders, of which the following is a specification.

This invention relates to a holder or support for order hoops, such as used in delivering orders from telegraphers to passing railroad trains and an object of the invention is to provide an order hoop holder adapted to be mounted alongside a railroad track adjacent a station for holding order 10 carrying hoops in position to be conveniently reached by engineers and conductors of passing trains and to hold in such a manner as to eliminate the necessity of slowing down the train to receive the orders 15 and also eliminate, to a material extent, the risk to the engineer and conductor and also to the stationman which is usually contingent with the handling of orders to a passing train.

20 Another object of the invention is to provide an order hoop holder as specified particularly designed for holding the order hoops and holders as disclosed in the application filed by me on July 10, 1920, Serial 25 No. 395,325, which holder is simple in construction and may be easily operated to move it into or out of operative position.

Other objects of the invention will appear 30 in the following detailed description and 35 in the accompanying drawing wherein:

Fig. 1 is a side elevation of the improved order hoop holder.

Fig. 2 is a top plan of the holder.

Fig. 3 is a section on the line 3—3 of 40 Fig. 1.

Fig. 4 is a side elevation of the order hoop used in connection with the improved holder.

Referring more particularly to the drawing the improved holder for order hoops 45 comprises a support 1 mounted upon a station platform as indicated at A and which carries a substantially oblong shaped guide 2, the said guide being supported in an inclined position and provided with a longitudinally extending slot 3 in which is slidably seated a block 4. A supporting arm 5 is pivotally connected to the block 4 and it preferably has its end adjacent the block forked to permit secure and firm connection

between the arm 5 and block 4. The arm 5 has its outer end 6 reduced in diameter and hollow to receive therein the handle 7 of the order hoop structure 8 shown in Fig. 4 of the drawing and more specifically illustrated and described in my companion application filed July 10, 1920, Serial No. 395,226. The end of the handle 7 is slipped or forced into the end of the tubular reduced section 6 of the arm 5 and the arm 5 is supported in position to permit an engineer or conductor on a passing train to grasp the hoop of the order holder structure 8 without slowing down the train. To assist the guide structure 2 in supporting the arm 5 a support 9 is provided which is pivotally connected as shown at 10 to the arm 5 intermediate the ends of the latter and which support has its lower portion spread providing spaced lugs 11.

By means of the longitudinal slot 3 in the link 2 the arm 5 may be supported at various elevations as required to properly position an order hoop carried thereby to be conveniently reached by a person on a passing train and it will also permit adjustment of the arm into position for placing the handle of the order hoop in reduced tubular end 6. When not in use, the entire device is swung over out of an operative position and to be out of the way of persons on the platform A.

It is, of course, to be understood that the invention may be constructed in various other manners and the parts associated in different relations and, therefore, I do not desire to be limited in any manner except as set forth in the claims hereunto appended.

Having thus described my invention what I claim is:

1. In an order hoop holder, a support comprising a guide supported at an incline, a block slidable in said guide, a hoop supporting arm pivotally carried by said block.
2. In an order hoop holder, a support comprising a guide supported at an incline, a block slidable in said guide, a hoop supporting arm pivotally carried by said block, and a support pivotally connected to said arm intermediate its ends, said arm having its free end longitudinally bored to receive the handle of the order hoop.

In testimony whereof I affix my signature.

OTTO F. KLOETZER.
